UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

DOUBLE-DRUM HOIST.

Application filed October 10, 1925. Serial No. 61,635.

To all whom it may concern:

Be it known that I, CHARLES C. HANSEN, a citizen of the United States, and a resident of Easton, county of Northampton, and 5 State of Pennsylvania, have invented a certain Double-Drum Hoist, of which the following is a specification accompanied by drawings.

This invention relates to hoists, but more 10 particularly to power driven hoists of the double drum type in which either of the drums may be driven from a common driving element.

In the type of hoist for which the present 15 invention is contemplated, the drums, commonly termed the haulage and tail rope drums, are usually mounted side by side, and are preferably mounted loosely upon their bearings so that they may rotate in opposite directions. This is especially desirable in hoists of the type illustrated in the drawings. Usually in this type of hoist an 20 end of a single rope or cable is secured to each of the drums and the load is secured to the loop thus formed. It is therefore desirable that the drum carrying the tail rope 25 rotate freely to unwind the rope while the other drum is winding up the rope.

In view of the foregoing facts, the means 30 for connecting the drums with the driving element should respond instantly and in a positive manner upon reversal of the driving element in either direction.

The objects of the invention are to insure 35 a positive driving connection between either of the drums and the driving element and to simultaneously disconnect the other drum from the driving element in accordance with the direction of rotation of the driving element.

Other objects will be in part obvious and in part pointed out hereinafter.

The invention consists of the combinations 45 of elements, features of construction and arrangement of parts having the general mode of operation substantially as hereinafter described and more particularly pointed out in the appended claims and illustrated in the accompanying drawings, in which—

50 Figure 1 is an elevation, partly in section, of a hoist constructed in accordance with the practice of the invention,

55 Figure 2 is a transverse sectional view through Figure 1 on the line 2—2 looking in the direction of the arrows, and

Figure 3 is a view similar to Figure 2 on the line 3—3 of Figure 1 looking in the direction of the arrows, showing one of the pawls in engagement with one of the opposed drum drivers. 60

Referring to the drawings, A indicates a base plate on one end of which is mounted a frame B and on the opposite end a motor C. The base plate A is preferably swivelled on a bed plate D and is held upon said bed 65 plate by a bolt E which may also serve as a pivot for the base plate A. The motor C may be of any suitable and compact type, but in this instance a fluid actuated motor of the flat piston type, commonly termed the 70 "Dake motor," is indicated. Pressure fluid for actuating the motor is introduced into a valve chest F through a suitable connection G and the distribution of the pressure fluid may be controlled by any suitable throttle 75 valve (not shown) located in the valve chest F. A throttle lever H connected operatively to the throttle valve serves as a convenient means for manipulating the valve and for reversing the direction of the motor. 80

In this instance a center bearing J extends longitudinally of the hoist and is supported at one end by the frame B and suitably secured thereto by means of screws K. The opposite end of the center bearing 85 J has formed integrally therewith a plate or flange L secured to the motor C by screws O and which plate serves as a side plate for the motor.

Extending through the center bearing J 90 is a main driving shaft P connected at one end to the motor to be rotated thereby. The other end of the driving shaft P is supported within a plate Q and is provided with an anti-friction bearing R. In addition to 95 forming a support for one end of the driving shaft P, the plate Q also acts as a cover for a gear casing S which in this instance is formed integrally with the frame B. 100

Arranged within the gear casing S is an intermediate gear T mounted on a stationary shaft U which is supported by the plate Q. The intermediate gear T in this instance is provided with anti-friction bearings V 105 and W and meshes with a driving pinion X keyed to the driving shaft P preferably between the bearing R and the frame B. An intermediate pinion Y preferably formed integrally with the intermediate gear T ex- 110

tends beyond the gear casing *S* and meshes with an internal gear *Z* mounted rotatably on the center bearing *J* and adjacent the frame *B*. In this instance the internal gear *Z* carries a cylindrical extension *b* which is journaled on the center bearing *J* and forms a bearing for a tail rope drum *c*. A haulage drum *d* is mounted rotatably upon the center bearing *J* adjacent the tail rope drum *c* and carries a drum driver *e* in the form of radial teeth, preferably formed integrally with the drum. A similar drum driver is formed on the drum *c*. The engaging faces of the drum drivers *e* and *f* are opposed with respect to each other for reasons which will be explained hereinafter.

In order to selectively engage or connect one or the other of the drums *c* and *d* to be driven by the driving shaft *P*, a main driver *g* is keyed to the extension *b* to rotate between the inner faces of said drums. In this instance, the main driver *g* is mounted eccentrically upon the extension *b* and forms a bearing for a sleeve *h* which is mounted rotatably thereon. In this instance the sleeve *h* has formed integrally therewith a pair of pawls *j* and *k* having a face *o* for engaging the drum drivers *e* and *f* of the drums *d* and *c* respectively. The pawls *j* and *k* are formed on opposite faces of the sleeve *h* so that the pawl *j* may engage the drum driver *f* and the pawl *k* may engage the drum driver *e*. In order to insure positive engagement of the pawls *j* and *k* with their respective drum drivers, an arcuate key slot *p* is formed in the sleeve *h* to cooperate with a stop or key *q* for limiting rotation of the sleeve *h* with respect to the main driver *g*. The pawls *j* and *k* are preferably off-set from the median line of the sleeve *h* toward which they incline so that the engaging faces *o* of said pawls are substantially in line with said median line. By thus off-setting the pawls, as described, the sleeve *h* will be unbalanced and will therefore always tend to swing toward the position illustrated in Figure 3.

Suitable means are provided for retarding or preventing rotation of the drums after they have been disconnected from the driving element. To this end a brake in the form of a band *r* encircles a flange *s* of the drum *d* and is provided with a suitable device as at *t* for tightening said band. Similarly a band *r* is arranged about the flange *u* of the drum *d* and like the band *r* on the flange *s* is also provided with suitable means for manipulating said band. Since the braking element herein shown together with its operation is well-known, further description thereof is considered unnecessary.

In the operation of the hoist, let it be assumed that the motor *C* is being actuated to rotate the shaft *P* in the direction of the

arrow adjacent said shaft in Figure 3. With the shaft *P* rotating in this direction, the train of gearing in the gear casing *S* together with the internal gear *Z* will cause the main driver *g* to rotate in a direction opposite to that in which the driving shaft is being rotated. Assuming then that the sleeve *h* is in the position shown in Figure 2, the main driver *g* may rotate until the stop or key *q* contacts with the end of the slot *p* as illustrated in Figure 3 and forces one of the pawls into engagement with its respective drum driver. However, it is not essential that the stop *q* should so strike the end of the slot *p* as the main driver *g* will positively actuate the sleeve *h* into an eccentric position with respect to the center bearing *J* so that one or the other of the pawls *j* and *k* will be moved into engagement with their respective drum drivers, depending upon the direction of rotation of the main driver.

Upon reversal of the motor the direction of the rotation of the driving shaft *P* and the train of gearing in the gear casing *S* together with the main driver *g* will accordingly be caused to rotate in an opposite direction to that required for driving the haulage drum *d*. At the instant of reversal the pawl *k* will be rocked out of engagement from the drum driver *e* and due to the eccentric motion of the main driver *g*, the pawl *j* will be carried into engagement with the drum *c* and thus connect the drum to be rotated in the direction of rotation of the main driver.

The pawls may be rocked into a neutral position in case it be desired to disengage both drums so that the cable or rope may be simultaneously unwound from both drums, but the clearance may be eliminated if desired, so that there is no neutral position.

I claim:

1. In a hoist, the combination of a base plate, a frame on one end of the base plate, a reversible motor at the opposite end of the base plate, a main driving shaft connected to be rotated by the motor, a center bearing encircling the driving shaft, drums rotatable about the center bearing, an eccentric main driver connected to be rotated by the driving shaft and rotatable about the center bearing, and means mounted rotatably about the main driver for connecting the main driver with one or the other of the drums in accordance with the direction of rotation of the main driver.

2. In a hoist, the combination of a base plate, a frame on one end of the base plate, a reversible motor at the opposite end of the base plate, a main driving shaft connected to be rotated by the motor, a center bearing encircling the driving shaft, drums rotatable about the center bearing, an ec-

centric main driver connected to be rotated by the driving shaft, said eccentric main driver being rotatable about the center bearing, and means including a sleeve 5 and pawls rotatable on the eccentric main driver whereby one or the other of said pawls are actuated into engagement with one of the other of said drums in accordance with the direction of rotation of the main 10 driver.

3. In a hoist, the combination of a base plate, a frame on one end of the base plate, a reversible motor at the opposite end of the 15 base plate, a main driving shaft connected to be rotated by the motor, a center bearing encircling the driving shaft and sup-

ported by the frame and the motor, drums rotatable about the center bearing, opposed drum drivers on said drums, an eccentric main driver connected to be rotated by the 20 driving shaft, said eccentric main driver being rotatable about the center bearing and the driving shaft, a sleeve carrying opposed pawls mounted rotatably on the eccentric main driver whereby one or the other of 25 the opposed pawls may be actuated into engagement with one or the other of the opposed drum drivers in accordance with the direction of rotation of the main driver.

In testimony whereof I have signed this 30 specification.

CHARLES C. HANSEN.
